(57) **CLAIM**

The ornamental design for a large tampon case, as shown and described.

DESCRIPTION

FIG. 1 is a perspective view of the top of the large tampon case with the lid shown in a closed position.

FIG. 2 is a perspective view of the top of the case with the lid open to show internal surfaces. Tampons are shown in broken line format in FIG. 2 and does not form any part of the design.

FIG. 3 is a front side view of the case.

FIG. 4 is a rear side view of the case.

FIG. 5 is a left side view of the case. The right side view is a mirror image.

FIG. 6 is a top view of the case; and,

FIG. 7 is a bottom view of the case.
